(57) **CLAIM**

We claim the ornamental design for an eco-friendly transaction device, as shown and described.

DESCRIPTION

FIG. 1 depicts a perspective view of a back face of an eco-friendly transaction device.

FIG. 2 depicts a front elevational view of FIG. 1.

FIG. 3 depicts a back elevational view of FIG. 1.

FIG. 4 depicts a bottom plan view of FIG. 1.

FIG. 5 depicts a top plan view of FIG. 1.

FIG. 6 depicts a side elevational view of FIG. 1.

FIG. 7 depicts an opposite side elevational view of FIG. 1.

FIG. 8 depicts a perspective view of the claimed design in a condition of use with broken line environmental structure.

FIG. 9 depicts a front elevational view of FIG. 8.

FIG. 10 depicts a back elevational view of FIG. 8.

FIG. 11 depicts a side elevational view of FIG. 8.

FIG. 12 depicts an opposite side elevational view of FIG. 8.

FIG. 13 depicts a bottom plan view of FIG. 8.

FIG. 14 depicts a top plan view of FIG. 8.

FIG. 15 depicts a perspective view of the claimed design in another condition of use with an alternate broken line environmental structure.

FIG. 16 depicts a front view of FIG. 15.

FIG. 17 depicts a bottom view of FIG. 15.

FIG. 18 depicts a side elevational view of FIG. 15.

FIG. 19 depicts an opposite side elevational view of FIG. 15.

FIG. 20 depicts an opposite side elevational view of FIG. 15; and,

FIG. 21 depicts an opposite side elevational view of FIG. 15. The broken lines in the drawings illustrate environmental structure on the article and form no part of the claimed design.
